UNITED STATES PATENT OFFICE.

WILBUR L. WRIGHT, OF FULTON, NEW YORK, ASSIGNOR TO SEALRIGHT CO., INC., OF FULTON, NEW YORK, A CORPORATION OF NEW YORK.

CLOSURE DISK FOR CONTAINERS.

1,403,532.

Specification of Letters Patent. Patented Jan. 17, 1922.

Application filed August 18, 1919. Serial No. 318,214.

To all whom it may concern:

Be it known that I, WILBUR L. WRIGHT, a citizen of the United States of America, and resident of Fulton, county of Oswego, 5 and State of New York, have invented certain new and useful Improvements in Closure Disks for Containers, of which the following is a specification.

This invention relates to certain improvements in closure disks for containers; and the objects and nature of the invention will be readily understood by those skilled in the art in the light of the following explanation of the accompanying drawings illustrating 15 what I now believe to be the preferred mechanical expression or embodiment of my invention from among other forms within the spirit and scope thereof.

An object of the invention is to provide 20 a flat single-ply pulp or paper material closure disk, the top and bottom surfaces of which are without projections so that the disk can be freely used in capping machinery, with the disk so cut in the process 25 of manufacture as to leave the disk approximately imperforate yet so that the disk will embody within itself a tongue-like portion that can be torn or separated except at one end, from the body of the disk to leave an 30 opening through the disk and to form a pull tab by which the disk can be extracted from the container mouth, and with the edge walls of the opening thus formed and of the tab, of such relative formation as to prevent 35 downward movement of said tongue-like portion before separation or of the tab after separation from the body of the disk, and furthermore to provide such disk formation, that cap making machinery in common use 40 can be easily modified to form the cuts in the disks as such machinery stamps or punches out the disks, whereby the disks can be economically manufactured in quantities without substantial increase in cost for 45 material and production over the common paper material disks of commerce that have no handle forming portions.

The invention consists in certain novel 50 features in construction and formation as more fully hereinafter set forth and pointed out.

Referring to the accompanying drawings:—

Fig. 1, is a top perspective view of the 55 disk of my invention.

Fig. 2, is a top perspective of the disk showing the tongue-like portion separated and bent up to form a pull tab and leave an opening through the disk.

Fig. 3, is a bottom perspective of the disk 60 of Fig. 2.

Fig. 4 is a top plan view.

Fig. 5 is a section on the line 5—5 Fig. 4.

Fig. 6 is a section on the line 6—6 Fig. 4.

In the drawings, I show a stiff flat closure 65 disk 1, composed of a single layer or ply of strong tough paper material or pulp board, such for instance as a special strong sulphite stock although I do not wish to so limit my invention.

70

This disk is cut partially through to provide or outline an approximately radial tongue-like area or portion 2 of the disk body or material extending from the top to the bottom faces of the disk and from the 75 inner or central part of the disk toward but terminating a substantial distance from the peripheral edge of the disk. This tongue-like portion includes areas of both the top and bottom surfaces of the disk, and is outlined or defined by an upper approximately 80 U-shaped cut *a* extending but partially through the disk, say about half way through the disk, and a lower approximately U-shaped cut *b* extending but partially through 85 the disk, say about half way. These two cuts are offset or out of alinement, i. e., the upper cut is larger or of greater width than the lower cut although approximately parallel or concentric therewith.

90

Although my invention is not concerned in form of each cut, whether of straight or curved lines or whether literally or strictly of a U-shape, yet in the drawings I happen to show each cut consisting of a curved cross 95 line at the inner end of the tongue-like portion with a pair of diverging lines extending from the ends of the cross line toward and terminating short of the disk edge. In this form, the cut extending down 100 through the top face of the disk is of greater width between its diverging lines and its cross line is nearer the center of the disk and of greater radius than the corresponding lines of the other cut that extends up 105 through the bottom face of the disk.

The arrangement of these upper and lower cuts is such that the tongue-like portion bounded thereby is throughout its length and width an integral connected portion of 110

- the disk, being so connected and secured in the disk by the unbroken portions *c* of the disk that intervene between the upper and lower cuts and by the uncut area of the 5 disk at the outer end or base of the tongue-like portion. These intervening or uncut portions of the disk are located under or beneath the area of the top surface of the disk that is bounded by the upper cut, but 10 are located outside of the area of the bottom surface of the disk that is bounded by the lower cut.

While the disk is composed of a homogeneous mass of pulp or paper material with 15 approximately hard finished surfaces, yet the intermediate portions of the material between the faces will separate under a comparatively light pull in the proper direction when the separation, in a plane approximately parallel with the disk faces, is once started. Nevertheless, the disk as an entirely possesses considerable tensile strength and stiffness and this tendency to easily split 20 does not exist except when a transverse pull is exerted on only a portion of the thickness 25 of the disk after the separation is started.

I utilize this peculiar quality or characteristic of these pulp board or other paper material disks, in the embodiment of my invention illustrated. The disks as manufactured, sold and used, are to all intents and purposes, flat and imperforate and similar to the common flat disks without handles. 30

However, when it is desired to extract a disk from a receptacle mouth, the finger nail can be inserted in the inner end of the upper cut, i. e. into the cross line thereof, and the separation can be thereby started by lifting the inner end of the tongue-like portion. 35

40 The finger nail laterally separates the unbroken intermediate material lying between the cross lines of the upper and lower cuts. The extreme end of the tongue-like portion is thus elevated and continued upward pull

45 causes splitting or separation of the material lying between the diverging lines of the upper and lower cuts until the complete pull tab is formed as shown by Figs. 2 and 3. This tab is the full thickness of the disk 50 except for the edge flanges *2^a*. The separation or splitting of the disk material ceases, on the upward movement of the pull tab, when the ends of the cuts are reached, and thereafter the pull is against the full thickness of the disk where the tendency to split 55 does not exist. The disk possesses considerable tensile strength against tearing through its full thickness and bracing or strengthening means to prevent the tab tearing through

60 the edge of the disk under disk extracting pull, is not necessary because the tab is of the full thickness of the disk.

If so desired, the top surface of the disk can be indented or depressed, at 5, at the 65 cross line of the upper cut, to visually indi-

cate to the user the point where the finger nail is to be inserted to initiate the separation and upward movement of the tongue-like portion, and to facilitate the entrance of the finger nail. This indentation can be 70 formed when the disk is cut. Also, if desired, the under surface of the disk can be indented or creased, see 6, at the base of the tongue-like portion to locate a bending line at the base of the tab or tongue and cause 75 the same to bend up easily and on an approximately straight transverse line.

These disks are always imprinted on their upper surfaces and furthermore the indent 5, will indicate the upper surface of the 80 cap, so that there will be no uncertainty in locating the disks right side up in the containers.

The formation and arrangement of the cuts prevents possibility of the tongue-like 85 portions becoming depressed into the containers through accident, either before or after separation. After the tongue-like portions have been separated and bent up, they can be bent back to place again to close the 90 openings, and the flanges *2^a* and shoulders *2^b* will prevent downward movement of the tabs into the containers. The tabs are hence free to move upwardly from but not downwardly through the disks. 95

The formation of the tab by separation and upward movement of the tongue-like portion, leaves an opening through the disk, and where it is not desired to remove the disk from the container, a pouring opening 100 is thus provided. Also, an opening through which paper straws can be inserted for consuming liquid contents direct from the container.

I do not wish to limit my invention 105 strictly to the tongue-like portion directly connected into the disk by unbroken material throughout the entire length of said portion, as the cross line at the inner end of said portion might be formed by an angular or inclined cut extending completely through the disk and formed by such a thin blade as to be closed by the paraffining treatment to which such disks are subjected. 110

These disks of my invention can be produced by the common gang punch presses now employed to stamp out the flat disks without handles as the punches and dies can be provided with thin blades to produce the 115 cuts.

The depression 5 is of sufficient depth and width to expose the extreme edge of the tongue-like area *2* approximately the full depth of the top cut *a*, so that the finger nail of the operator can easily enter the depression and initiate the separation of the internal intermediate unbroken connecting portion of the disk between the curved cross portions of the cuts *a*, *b*. 125

The depression 5 is formed by male and 130

female dies so that a portion of the disk is depressed bodily from the plane of the disk forming a projecting bulge at the bottom of the disk, see 5', Figs. 3 and 5, and this bottom bulge is beveled or rounded so as to offer no abrupt or like edge portions or shoulders to interfere with the free use of the disks in capping machinery.

It is evident that variations in formation and arrangement can be resorted to without departing from the spirit and scope of my invention and hence I do not wish to limit myself to the exact disclosure hereof.

What I claim is:—

- 15 1. A flat single-ply paper-material closure disk having upper and lower offset cuts outlining a tongue like portion of the full thickness of the disk and adapted to be bent up to form a pull tab and leave an opening 20 through the disk, said disk formed with a depression at the inner end of said portion, said depression forming a rounded or bevelled edge bulge at the under side of the disk.
- 25 2. A flat single-ply paper-material closure disk at its top and bottom faces formed for use in capping machinery and having upper and lower offset cuts outlining a tongue-like portion of the full thickness of the disk and 30 adapted to be bent up to form a pull tab and leave an opening through the disk remote from the disk edge, said disk being imperforate and at its top face formed to render the end of said portion accessible.
- 35 3. A flat paper material closure disk having offset cuts at its opposite side faces extending partially through the thickness of the disk and outlining a tongue-like portion of the full thickness of the disk remote from 40 the disk edge and formed to be bent up to leave an opening through the disk and form

a free end pull tab within the boundary of the disk, said disk being formed for use in capping machinery and having a top depression partially exposing the end edge of said portion. 45

4. A flat paper material disk embodying and including within itself a tongue-like portion of the full thickness of the disk and approximately throughout its full length 50 joined to the disk by uncut readily separable intermediate portions of the material of the disk, the area of the top surface of the disk that forms the top surface of said portion being of greater width than the area of 55 the bottom surface of the disk that forms the bottom surface of said portion, said disk being closed completely around said portion against passage of liquid and formed to permit access of a finger nail to the inner end of 60 said portion to enable said portion to be bent up to form a pull tab having its base spaced a substantial distance from the disk edge.

5. A flat paper material disk providing within its surrounding edge, a tongue-like 65 portion of the full thickness of the disk and joined in the disk throughout its length including its inner end by imperforate uncut readily-separable intermediate portions of the material of the disk, the area of the top 70 surface of said portion that forms an intermediate part of the disk top being of greater width than the area of the bottom surface of said portion that forms an intermediate part of the disk bottom, said disk 75 being formed to permit access to said inner end of said portion to enable said portion to be partially detached and bent up to form a disk-extracting pull tab and to provide a pouring opening spaced from the outer sur- 80 rounding edge of the disk.

WILBUR L. WRIGHT.
